UNITED STATES PATENT OFFICE

125,376

DESIGN FOR A DRESS ENSEMBLE

Anna Naubert, Chicago, Ill.

Application December 20, 1940, Serial No. 97,476

Term of patent 3½ years

To all whom it may concern:

Be it known that I, Anna Naubert, a citizen of the United States, residing at 7728 Marshfield Avenue, Chicago, in the county of Cook and State of Illinois, have invented a new, original, and ornamental Design for a Dress Ensemble, of which the following is a specification, reference being had to the accompanying drawings, forming part thereof.

I claim:

The ornamental design for a dress ensemble, substantially as shown.

ANNA NAUBERT.
